(57) **CLAIM**

The ornamental design for a hand tool handle with knob, as shown and described.

DESCRIPTION

FIG. 1 is a perspective view of a hand tool handle with knob.

FIG. 2 is a left side elevation of the hand tool handle with knob. A right side elevation of the hand tool handle with knob is not shown because it is a mirror image of the left side elevation.

FIG. 3 is a top plan view of the hand tool handle with knob.

FIG. 4 is a bottom plan view of the hand tool handle with knob. The hand tool handle with knob is shown as a separate part to facilitate viewing of the hand tool handle bottom portions.

FIG. 5 is a front elevation of the hand tool handle with knob; and,

FIG. 6 is a rear elevation of the hand tool handle with knob.

The broken lines are directed to the environmental structure defining the boundary of the claimed portions of the hand tool handle with knob and form no part of the claimed design.
